UNITED STATES PATENT OFFICE

154,951

DESIGN FOR A CRIB LIGHT OR SIMILAR ARTICLE

Leo Packman, New York, N. Y.

Application January 8, 1948, Serial No. 143,587

Term of patent 7 years

(Cl. D48—20)

To all whom it may concern:

Be it known that I, Leo Packman, a citizen of the United States of America, residing in New York city, county of New York, and State of New York, have invented a new, original, and ornamental Design for a Crib Light or Similar Article, of which the following is a specification, reference being had to the accompanying drawing, forming part thereof, wherein,

Figure 1 is a front perspective view of a crib light, showing my new design.

Figure 2 is a front elevational view.

Figure 3 is a side elevational view, and

Figure 4 is a bottom plan view of the crib light shown in Figures 1, 2, and 3.

The drawing is shaded to indicate color.

I claim:

The ornamental design for a crib light or similar article, substantially as shown and described.

LEO PACKMAN.
